UNITED STATES PATENT OFFICE

FRANK A. FALK, OF STACYVILLE, IOWA, ASSIGNOR TO CHICAGO FORGING & MANUFACTURING CO., OF CHICAGO, ILLINOIS, A CORPORATION OF ILLINOIS

HOOD LATCH

Application filed January 2, 1932. Serial No. 584,463.

My invention relates to an improvement in automobile hood latches and is particularly adaptable to employment with multiple hinge hood closures for automobiles. One object 5 is the provision of such a device which shall include an exterior handle and interior latching means positioned within the hood closure. Another object is the provision of a device 10 which shall include a single exterior handle whereby a plurality of interior latching means may be moved into and out of securing engagement with a keeper or keepers. Other objects will appear from time to time in the course of the specification and claims.

15 I illustrate my invention more or less diagrammatically in the accompanying drawings, wherein—

Figure 1 is a side elevation :

Figure 2 is a partial interior elevation on an enlarged scale:

Figure 3 is a section on the line 3-3 of Figure 2:

Figure 4 is a section on the line 4-4 of Figure 2;

Figure 5 is a view similar to Figure 2 with parts in unlocked position; and

Like parts are indicated by like symbols throughout the specification and drawings.

Referring to the drawings, A generally indicates a portion of the automobile frame, A¹ is the radiator, A² is the lower hinge member of the automobile closure, being hinged to the upper member A³ which is hinged to the automobile as at A⁴. A¹¹ indicates the dash or cowl.

40 Positioned within said closure and spaced more or less therewithin are the keeper brackets generally indicated as B which include a bottom flange B¹, an upwardly extending portion B² and a hook portion B³ inclined downwardly and outwardly toward the inner face of the hood closure. The bracket or keeper so formed may be secured to the frame by any suitable securing means. I illustrate the bolt B⁴ with the nut B⁵.

50 Rotatably mounted upon the inner face of the closure for rotation about a generally horizontal axis is the rock shaft or rod C. I

illustrate it as rotatably supported with sleeves or bearings C^1 adjacent the central portion thereof, and C^2 adjacent the ends thereof. Beyond the bearing C^2 the ends of the rod are curved as at C^3 and terminate in portions C^4 which extend in general parallelism with the rod itself. It will be understood that whereas I have shown a particular type of crank end for the rod C , that I do not wish to be limited specifically to the particular crank herein shown, although I find it an efficient solution of the problem. The keeper also may be varied in form and location, depending upon the nature of the crank employed.

In order to rotate the rod C in such fashion as to move the crank members C³ C⁴ into and out of latching association with the keeper hooks B³ I employ the following mechanism. I provide a central offset D in the form of a loop in the rod C. I illustrate it as located between the two central bearing sleeves C¹ although its location in relation to the length of the rod may be varied if desired. In the particular exemplification of my invention herein shown the loop D lies in a plane generally perpendicular to the long axis of the rod C. This is clear for example from Figures 2 and 3. In order to rotate the

loop, and thus rotate the rod C, I employ an exterior handle D¹ which may be mounted on a handle shaft D². Held against movement in relation to the handle D¹ and shaft D² is a hook shaped actuating member which includes the base portion D³ secured to the shaft D². The assembly may be held together for example by the nut D⁴ in mesh with a screw threaded end portion D⁵ of the shaft D². I illustrate this as an example of a means for holding the parts together as any other suitable means may be employed. Extending outwardly from the base portion D³ is a hook shaped member D⁶ which terminates in an enlargement or stop portion D⁷. It will be seen as from Figure 3, that the shank of the hook D⁶ is more or less outwardly inclined as at D⁸. The base portion D³ is provided with a face D⁹ which serves to limit the movement of the loop D along the hook shank in one direction, while the enlargement 10

- D^7 limits it in the opposite direction. As will be seen, for example, in Figure 6, the inclined portion D^8 terminates, adjacent its axis of rotation in a rectilinear portion D^{11} .
5 The inner face of the hook is generally curved as at D^{10} , this curved portion engaging the inner surface D^{12} of the closed lip D , as shown in Figures 5 and 6, when the device is in unlatched position and is being moved 10 initially toward the latched position.

It will be realized that whereas I have described and shown a practical and operative device, nevertheless many changes may be made in size, shape, number and disposition 15 of parts without departing from the spirit of my invention. I therefore wish my description and drawings to be taken as in a broad sense illustrative and diagrammatic rather than as limiting me to my specific 20 showing. The use and operation of my invention are as follows:

Assume that the securing means are in the unlocked position as shown for example in Figure 5, with the actuating member or hook 25 D^6 rotated, in counter-clockwise rotation as far as it will go. The enlargement D^7 is of such size as not to pass through the loop D and it therefore limits the movement of the handle which may, as a matter of convenience, as shown in the particular exemplification 30 herein, be in vertical position when in the unlocked position. Referring to the parts in the position in which they are shown in Figure 5, if the operator rotates the handle 35 D^1 in clockwise direction, he causes the curved hook shank D^6 to penetrate more deeply the loop D . It has in relation to the loop a camming action, causing the loop to move upward to rotate. This camming action 40 may be obtained, as herein shown, by forming the shank D^6 with the generally arcuate loop engaging face D^{10} , the center of the arc being eccentric to the center of rotation of the hook. Thus, its clockwise rotation 45 draws the loop nearer and nearer the center of rotation. The loop is preferably so proportioned that the actuating member seats against its upper end to hold the handle horizontal. The flange D^8 on the actuating 50 member also acts as a heel or stiffener to restrain distortion or mis-alignment of the handle shaft D^2 . As the center of rotation of the handle and cam is above the center of rotation of the rod C , the loop is rotated 55 until it reaches the upper position in which it is shown in Figure 2. Its further rotation may be limited for example by its engagement with the face D^9 . When it reaches this position the handle D^1 , in the present embodiment, is in horizontal position, and the crank members C^3 C^4 have been moved to their locking or latching position and the members C^4 engage the hooks B^3 as shown, 60 for example in Figures 2 and 4. A reverse 65 rotation of the handle D^1 returns the parts

to the position in which they are shown in Figures 5 and 6, with the crank members C^3 C^4 snugly against the inner face of the closure A^2 . This is the position in which they are shown in Figure 6, and an upward 70 lift by the operator on the handle is effective to lift the closure freely upwardly.

I claim:

1. For use with a latching device for the multiple hinge closure of an automobile hood, a rod rotatably mounted upon the inner face of the closure for rotation about a generally horizontal axis, and means for rotating said rod including an exterior handle mounted for rotation about an axis generally perpendicular to the axis of rotation of the rod, a closed loop associated with said rod and held against rotation in relation thereto and an actuating member, penetrating said loop, associated with and rotatable in unison with 85 said handle.

2. For use with a latching device for the multiple hinge closure of an automobile hood, a rod rotatably mounted upon the inner face of the closure for rotation about a generally horizontal axis, and means for rotating said rod including an exterior handle, a closed loop associated with said rod and held against rotation in relation thereto, said loop lying in a plane generally perpendicular to the axis of rotation of the rod, and an actuating member penetrating said loop, associated with and rotatable in unison with 90 said handle.

3. For use with a latching device for the multiple hinge closure of an automobile hood, a rod rotatably mounted upon the inner face of the closure for rotation about a generally horizontal axis, and means for rotating said rod including an exterior handle, a closed loop associated with said rod and held against 100 rotation in relation thereto, and an actuating member penetrating said loop, associated with and rotatable in unison with 105 said handle.

4. For use with a latching device for the multiple hinge closure of an automobile hood, a rod rotatably mounted upon the inner face of the closure for rotation about a generally horizontal axis, and means for rotating said rod including an exterior handle, a closed loop offset integral with said rod, and an 110 operating member penetrating said loop, associated with and rotatable in unison with said handle.

5. For use with a latching device for the multiple hinge closure of an automobile hood, a rod rotatably mounted upon the inner face of the closure for rotation about a generally horizontal axis, and means for rotating said rod including an exterior handle, a loop associated with said rod and held against rotation in relation thereto, and an actuating member, penetrating said loop, associated with and rotatable in unison with said handle, and stop means at the outer end of 120 said handle.

125

130

actuating member, adapted to prevent its withdrawal through said loop.

6. For use with a latching device for the multiple hinge closure of an automobile hood, a rod rotatably mounted upon the inner face of the closure for rotation about a generally horizontal axis, and means for rotating said rod including an exterior handle, a loop associated with said rod and held against rotation in relation thereto, and an actuating member, penetrating said loop, associated with and rotatable in unison with said handle, and stop means at the opposite ends of said actuating member, adapted to limit the movement of said cam member into and out of said loop.

7. For use with a latching device for the multiple hinge closure of an automobile hood, a rod rotatably mounted upon the inner face of the closure for rotation about a generally horizontal axis, and means for rotating said rod including an exterior handle, a closed loop offset integral with said rod, and an actuating member penetrating said loop, associated with and rotatable in unison with said handle.

8. For use with latching means for the double hinged closure of an automobile hood, a rock shaft mounted on the interior of the hood for rotation about a generally horizontal axis, and means for rotating said shaft, including a closed loop unitarily movable with said shaft, an exterior handle, and an actuating member movable in response to movement of said handle, penetrating said closed loop.

9. For use with latching means for the double hinged closure of an automobile hood, a rock shaft mounted on the interior of the hood for rotation about a generally horizontal axis, and means for rotating said shaft, including a closed loop unitarily movable with said shaft, an exterior handle, and an actuating hook movable in response to movement of said handle, penetrating said closed loop, said hook having a cam surface on one face and an additional cam cam surface on another face.

Signed at Osage, county of Mitchell and State of Iowa, this 9th day of December, 1931.

FRANK A. FALK.
